A. M. GRIFFIN,
GASOLENE TOWER,
APPLICATION FILED AUG. 24, 1918.

1,311,271.

Patented July 29, 1919.

UNITED STATES PATENT OFFICE.

ALVAH M. GRIFFIN, OF KANSAS CITY, MISSOURI.

GASOLENE-TOWER.

1,311,271.

Specification of Letters Patent. Patented July 29, 1919.

Application filed August 24, 1918. Serial No. 251,312.

To all whom it may concern:

Be it known that I, ALVAH M. GRIFFIN, a citizen of the United States, residing at Kansas City, in the county of Jackson and State of Missouri, have invented certain new and useful Improvements in Gasolene-Towers, of which the following is a specification.

This invention relates to gasolene towers of that class for use at filling stations, and the object of the invention is to produce a tower in which danger of explosion or the like is minimized by storing the gasolene underground, and by which the gasolene can be raised to an observation cylinder by air pressure and any excess quantity raised can be returned to the underground storage point.

A further object is to produce a gasolene tower provided with a register for showing the quantity of gasolene which has been dispensed, and a siphon adjustable to accurately control the quantity of gasolene dispensed and to prevent the register from recording a greater quantity of gasolene than has actually been dispensed.

A still further object is to provide a gasolene tower embodying an adjustable siphon of the type mentioned, by which excess gasolene supplied to the observation cylinder may be withdrawn therefrom to the underground storage point.

With these objects in view the invention consists in certain novel and useful features of construction and combinations of parts as hereinafter described and claimed; and in order that it may be fully understood reference is to be had to the accompanying drawing, in which:

Figure 1, is a side elevation of a gasolene tower embodying my invention.

Fig. 2, is an enlarged central vertical section of a part of the tower.

Fig. 3, is a fragmentary horizontal section on the line III—III of Fig. 2.

Fig. 4, is a face view of a part of the tower upright, to disclose the rack bar for effecting adjustment of a siphon forming part of the invention.

Fig. 5, is an enlarged horizontal section of a plural-way valve, controlling the flow of gasolene to and from the observation cylinder forming a part of the tower.

Referring to the drawing in detail, 1 indicates a hollow tower stand surmounted pref-

erably by a transparent observation cylinder 2 and arranged within said cylinder is a float 3 guided to move vertically upon guide rods 4 extending from the top to the bottom of the cylinder. The float is provided with a rack bar 5 extending up through the top of the cylinder and into a guide tube 6 mounted upon the cylinder. The rack bar meshes with a cog pinion 7 forming a part of a register of common and well known type 8 which shall operate when turned in one direction only, viz., when the rack bar moves upwardly. As registers of this character are common and no claim is made to the same except as an old element in a new combination, detailed showing and a description of the register is omitted, it being understood that as shown the rack bar continuously engages the cog wheel, and hence when moving downward, turns said cog wheel inoperatively, that is without affecting the counting mechanism of the register.

A siphon comprises a pipe consisting preferably of two stationary sections 9 and 10, and a slideable inverted U-shaped section 11, one leg of the section 11 fitting telescopically in stationary section 10 which is also utilized in conjunction with a nut 12 in clamping the heads of the cylinder in place. The short leg of the siphon comprises the other leg of said inverted U-shaped section 11, which leg extends slidingly through the upper head of the cylinder and has a laterally projecting foot 13 to limit upward traveling movement of the float, so that the latter cannot cause the register to record a sale of gasolene greater than that indicated by the adjustment of the slideable section of the siphon. To adjust the siphon a rod 14 is attached to the movable section of the siphon and extends slidingly through the heads of the cylinder and through a tube 15 extending from one of said heads to the other, the tube being employed to guard against leakage of gasolene from the cylinder around the rod 14. The lower end of the siphon adjusting rod 14 is provided with an outwardly projecting handle 16 extending through a vertical guide slot 17 in a bracket 18 secured to and preferably within the tower stand 1, one wall of said slot being ratchet toothed to provide a series of shoulders spaced apart to represent half gallons or any other predetermined meas-

urements, that is to say when the handle occupies a position opposite shoulder 2 of the vertical gage scale indicia appearing in Fig. 4, the lower end of the short leg of 5 the siphon is disposed within the cylinder 2 at the level to which two gallons of gasoline will fill said cylinder. The rod 14 will preferably be resilient and tend to ride up the slot against the serrated or toothed wall 10 thereof so that it will automatically retain its position upon any of the shoulders 19. When the siphon is to be lowered, lateral pressure is applied on the rod so that the handle may be slid downward to one side 15 of the line of shoulders.

20 is a storage tank set underground or at any suitable point, and provided with a filling tube 21, which also serves as an air vent for said tank. It is also provided with a discharge tube 22 equipped with a check valve 23, and leading into a small tank 24, the latter preferably being of less capacity than the observation cylinder. The lower end of 25 section 9 of the siphon communicates with tank 24. 25 is a pipe leading from an air pressure tank or the like to a two-way valve 26 arranged within the tower stand and accessible through a door controlled opening 27 thereof. Two other pipes 28 and 29 communicate with the casing of valve 26 at suitable points, and with the tanks 24 and 20 respectively, and the valve is operable by handle 30 so that pipes 25 and 28 or 28 and 29 may be connected together by the valve.

35 The tank 24 will always stand charged with gasoline as long as the main or supply tank contains any gasoline, as the check valve 23 opens toward tank 24. Assuming that a person calls for two gallons of gasoline, the attendant will adjust the siphon to the position shown in Fig. 2, by proper manipulation of handle 16 with reference to the scale in proximity to the slot 17. As soon as the siphon is thus adjusted, the attendant will operate valve 26 to establish communication between the air supply pipe 25 and the pipe 28, so that air under pressure may enter tank 24 and force gasoline up through the siphon and into the observation cylinder, closing the said valve preferably when the level of the gasoline in the cylinder reaches the bottom of the short leg of the siphon, as this level will indicate that two gallons of gasoline stand in the cylinder. It will, of course, be apparent that as the gasoline accumulates in the cylinder, the float will rise until arrested by contact with the laterally projecting foot of the siphon, and in such upward movement will 50 operate the register to record the fact that two gallons of gasoline have been sold.

To discharge the predetermined quantity of gasoline from the cylinder, the latter is provided with a valve controlled discharge pipe 31, to which a flexible hose, not shown,

is adapted to be attached for delivery of the gasoline to the tank of an automobile or to any other receptacle.

In the event that the attendant fails to check the supply of gasoline to the observation cylinder when the quantity therein equals the amount desired, and in consequence the gasoline accumulates in said cylinder to a level above the lower end of the short leg of the siphon, it will be apparent 75 that the excess quantity can be withdrawn from the observation chamber by simply manipulating valve handle 30 to close communication between pipes 25 and 28 and open communication between pipes 28 and 29. 80 Immediately the pressure is removed, the gasoline in the long leg of the siphon flows downward into tank 24, and establishes a siphonic action from cylinder 2, which action it continues until the siphon 85 is broken by the level of the gasoline in the cylinder falling below the bottom of the short leg of the siphon. In the event that the excess of gasoline returned to the tank 24 is so great that said tank will not hold 90 it, the gasoline will back up through pipe 28 and the valve 26, and then flow through pipe 29 into the main or supply tank 20.

From the above description it will be apparent that I have invented a gasoline tower 95 for filling stations which embodies all of the features pointed out as desirable, and while I have described and claimed the preferred embodiment of the invention it is to be understood that I reserve the right to all 100 changes which may properly fall within the scope of the appended claims.

I claim:

1. A gasoline tower comprising a supply tank, an elevated tank for containing a measured quantity of gasoline, and a siphon for conducting gasoline from the supply tank to the elevated tank and for withdrawing all gasoline from the last-named tank standing above the level of the short leg of the siphon.

2. A gasoline tower comprising a supply tank, an elevated tank for containing a measured quantity of gasoline, a siphon for conducting gasoline from the supply tank to the elevated tank and for withdrawing all gasoline from the last-named tank standing above the level of the short leg of the siphon, and valve controlled means for admitting air pressure for effecting a flow of gasoline through said siphon into said elevated tank or for cutting off such pressure to permit the siphon to withdraw gasoline from the elevated tank in the event the short leg of the siphon is sealed by gasoline in said elevated tank.

3. A gasoline tower comprising a main supply tank, an auxiliary supply tank at a lower level than the main supply tank and connected to be supplied by the latter, a

- check valve on the supply line between said tanks and adapted to open toward the auxiliary tank only, an elevated tank, and a siphon communicating at the lower end of its 5 longer leg with the auxiliary supply tank and at the lower end of the short leg with said elevated tank, a pipe for supplying air under pressure, a pair of pipes connected respectively with the said supply tanks, and 10 a valve controlling said last-named pipes and said air supply pipe and adapted to establish communication between the air supply pipe and the last-named pipe connected to the auxiliary supply tank, or to cut off 15 the air supply pipe and establish communication between the other pair of pipes.
4. A gasolene tower comprising an elevated tank, a siphon comprising a stationary portion connected to a gasolene supply and 20 an upper or slideable portion communicating with said tank, and means for adjusting the slideable portion to change the level of the lower end of the short leg of the siphon, within said tank.
- 25 5. A gasolene tower comprising an elevated tank, a siphon comprising a stationary portion connected to a gasolene supply and an upper or slideable portion communicating with said tank, means for adjusting the 30 slideable portion to change the level of the lower end of the short leg of the siphon, within said tank, and means for securing the slideable portion of the siphon at the desired point of adjustment.
6. A gasolene tower comprising a tank, a siphon comprising a stationary portion extending upwardly beyond the tank, and a slideable portion fitting the stationary portion telescopically and also extending down into the said tank, a slide rod having a 35 handle, and a bracket provided with a vertical slot through which said handle projects and with a series of shoulders at one side of said slot for engagement by the handle to prevent accidental adjustment of the slideable portion of the siphon.
7. In a gasolene tower, a tank, a siphon for supplying gasolene to or withdrawing an excess quantity of gasolene from said tank, and comprising a stationary portion 50 and a vertically adjustable portion terminating short of the lower end of the stationary portion, means for securing the slideable portion with its lower end at the desired elevation within said tank, a register, a suitably guided float within the tank to be arrested in its upward movement by the short leg of the siphon, and means to transmit power from said float to said register.
- In testimony whereof I affix my signature. 55

ALVAH M. GRIFFIN.
